Walker W. Stanard, of Buffalo, N. Y.
Assignor to
Jewell and Root, of same place.
Model No. 1401. Letters Patent No. 36, dated April 9, 1861.

The schedule is referred to in these Letters Patent and making part of the same.

To all whom it may concern:

Be it known that of Walker W. Stanard, of the City of Buffalo, County of Erie and State of New York, assignor to Jewell and Root of the same place, have invented or produced a certain new and original ornamental design for

elevated oven for cook stoves which I denominate by the name of "Sovereign" and I do hereby declare that the following is a full and exact description of the same, reference being had to the accompanying photographic plates, and the letters of reference marked thereon, in which-

Fig. I. represents one of the side plates of the oven.

Fig. II. represents one of the end plates and door of the oven, and

Fig. III. represents the top plate.

The side plate Fig. I, is surrounded by a finely denticulated and beaded edge, mounting (a).

The central ornament consists of the embossed medallions (b), with a fine fluting and fillets between them entering in the embossed ornament (c).

This central ornament as described is surrounded by embossed scrolls (d), leaves (e) and curved or scroll mouldings (f), arranged and combined with each other as represented in the plate.

Near the upper edge of the plate is the name of the stove "Sovereign" in embossed letters. The opposite side plate is the same in all respects as the one just described.

The end plate Fig. II, is surrounded by the denticulated and scalloped edged moulding (g) similar to the moulding (a) surrounding the side plate Fig. I. (h) represents the oven door its upper corners being rounded, and surrounded by plain concave and convex mouldings and the denticulated moulding or border (i). In the centre of the door is an oval emboss. (j) with radiating corrugations (k) surrounded by the embossed scrolls and leaves (l), arranged as represented in the plate.

The opposite end plate is the same in all respects except that the door is made a stationary panel.

The top plate Fig. III, is surrounded by the ornamental embossed moulding or border (m) as shown in the plate.

Claim the ornamental design for elevated oven for cook stove herein described and represented in each of the accompanying photographic plates
